UNITED STATES PATENT OFFICE

137,806

DESIGN FOR A SUNGLASS CIGARETTE LIGHTER

Lawrence H. Duescher, Milwaukee, Wis.

Application February 2, 1944, Serial No. 112,417

Term of patent 3½ years

(Cl. D48—27)

To all whom it may concern:

Be it known that I, Lawrence H. Duescher, a citizen of the United States and resident of Milwaukee, in the county of Milwaukee and State of Wisconsin, have invented a new, original, and ornamental Design for a Sunglass Cigarette Lighter, of which the following is a specification, reference being had to the accompanying drawing, forming part thereof.

Figure 1 is a perspective view of a sunglasses cigarette lighter, showing my new design.

Figure 2 is a top, plan view of the lighter showing the same in its flat unfolded condition, and

Figure 3 is a side elevational view of the lighter showing the same in its collapsed folded condition.

I claim:

The ornamental design for a sunglasses cigarette lighter, as shown.

LAWRENCE H. DUESCHER.
